[57] CLAIM

The ornamental design for ornaments for flush handles, as shown and described.

DESCRIPTION

FIG. 1 is a top, right side perspective view of ornaments for toilet flush handles, showing my new design, the broken line showing is for illustrative purposes only and forms no part of the claimed design;

FIG. 2 is a rear, top, left side perspective view thereof,
and

FIG. 3 is a bottom plan view thereof.

FIG. 1.

FIG. 2.

FIG. 3.
